UNITED STATES PATENT OFFICE

ANTON ZEINDLHOFER, OF VIENNA, AUSTRIA, ASSIGNOR TO GROOVE LOCK CO. INC., OF NEW YORK, N. Y., A CORPORATION OF NEW YORK

FOLDING RECEPTACLE

Application filed February 21, 1928. Serial No. 255,866.

This invention relates to improvements in receptacles, such as hand-bags and other containers, provided with means which can be moved apart or folded together to open and close the receptacle.

5 An object of the invention is to provide a receptacle containing a plurality of compartments or pockets adapted to be opened and closed separately, and equipped with simple but easily operated and effective means for securing the mouth of the bag; so that all 10 the pockets or compartments may be kept closed, or opened at will when access to any one or all of said compartments is desired.

15 The nature of the invention is fully disclosed in the following description taken with the accompanying drawing, which illustrates one embodiment of the invention, but the disclosure is explanatory only and I may vary the details of construction without departing 20 from the principle of the invention as the latter is defined in the appended claims.

On the drawing,—

Figure 1 is a side view of a receptacle in 25 the form of a handbag or the like according to my invention,

Fig. 2 is a similar view of the top thereof enlarged,

Fig. 3 is a view of what is shown in Fig. 2, 30 seen from the left,

Fig. 4 is a similar view to Fig. 2 showing one part of the bag opened to give access to one compartment,

Fig. 5 is an end view of what is shown in Fig. 4 viewed from the left,

Fig. 6 is a view similar to Fig. 2 showing the parts in position to give access to all compartments,

Fig. 7 is a view of what is shown in Fig. 6, 40 seen from the left,

Fig. 8 is a section along 8—8 of Fig. 2, and

Fig. 9 is a sectional view along the line 9—9 of Fig. 2.

The same numerals identify the same parts 45 throughout.

While I have shown the invention as practiced in connection with a handbag of cloth or other collapsible material, I may obviously employ a similar construction for valises and 50 other casings or containers in which the es-

sential features of my invention may be incorporated.

As indicated in the drawing, I use the numeral 1 to indicate a pair of frames or hinge members; these members each being in 55 the form of an inverted U hinged together at 2. The body of the receptacle which is shown as a cloth bag 3 is secured to the inner edges of these frame members along the edges of its mouth, so that to open the receptacle 60 the frames are separated and to close the same they are moved together. Between the two members 1 is a similar frame member 4 of the same size and shape also connected to the hinges 2, and at the corners of the intermediate frame member 4 and on the outside of the same are loops 5 to be attached to the ends of a carrying strap 6. As shown in Figs. 8 and 9 the inner edge of the intermediate member may be channel shaped or 65 grooved to receive the edges of a pair of partitions 7 which are secured to the member 4 from one hinge 2 to the other and to the sides and bottom of the bag 3 on the interior of 70 the same. The sides of the bag may also be lined with suitable cloth or fabric shown at 75 8. This fabric may be connected along its edges to the edges of the partitions 7. Hence between each of the partitions or layers of cloth 7 and the lining 8 will be a pocket 9; two of these pockets 9 or compartments being 80 shown; and the user, of course, may put in one of these pockets anything which he desires to keep separate from the contents of the other, by swinging away from the intermediate member 4 one of the frame members 1. One of these pockets can be opened while 85 the other can be closed or both can be opened at will.

The frames 1 may be channel shaped as indicated in the cross-sectional views of Figs. 8 and 9 and the edges of the mouth of the bag 3 and linings 8 may be secured within the grooves or channels afforded by these frame members 1. The inside of the members 1 may be provided with metal strips 10 extending along the tops of the frame members 1 to abut the sides of the intermediate member 4 when the receptacle is fully closed, 90 and the tops of the strips 10 project above 95 100

the tops of the frames 1. Each strip or plate 10 will have its upper or outer edge formed to provide a pair of ribs 11 and 11—a extending laterally; the ribs 11 and 11—a of one strip projecting to one side of the bag and the ribs of the other strip projecting to the opposite side of the bag. These ribs are separated by a space 12 adjacent the middle of the bag, and each rib 11 may be the longer of the two and be joined adjacent the middle of the frame 1 to a stop 13 which is formed on the plate 10. The two strips 10 as indicated in Figs. 7 and 8 have the ribs 11 and 11—a thereon arranged reversely with respect to each other, so that the rib 11 of one strip is adjacent the rib 11—a of the other; and the two spaces 12 will not be directly opposite, but will be disposed each a little away from the middle of its plate 10; one space towards one end and the remaining space towards the opposite end. The purpose of this construction will appear presently.

Mounted on the top of the intermediate frame member 4, which will have the cross sectional shape of the head of a rail, are sliding means in the form of a pair of catches or securing elements 14 and 18. Each of these elements will have projections to go under the top of the intermediate member 4, as shown at 15 in Fig. 8; and other inwardly extending projections 16 to engage the ribs 11 and 11—a along the tops or outer edges of the strips or plates 10. As indicated in Fig. 8, the inward extending projections 15 and 16 of each of the catches 14 and 18 are disposed on both sides of each catch; so that when these catches are mounted on the frame 4 they can engage the rails 11 and 11—a of both strips 10. The strips 10 project above the frames 1 not over the full length of the tops thereof, but the parts which carry the rails 11 and 11—a and project above the tops of the frames 1, terminate short of the ends of the tops; so that the ribs 11 and 11—a have a combined length that is less than the length of the tops of the frames 1 between the loops 5. At its two ends the inner frame member 4 has a rib 17 in line with ribs 11 and 11—a so that when either of the catches is slipped along the rail-shaped top of the member 4 it can move not only along the rails 11 and 11—a but also along the rail 17 and off the rails 11 and 11—a when the rails 17 are reached. The member 4 carries four such short rails or ribs 17, two at each end on the opposite faces or sides of same. The intermediate frame member 4 carries a fixed stop 19 at the middle to limit the movement of the elements 14 and 18 towards each other; and the numeral 20 indicates tabs or flaps secured to the frames 1 at the middle of the bag to afford a hold when the bag is to be pulled open.

With the catches 14 and 18 as shown in the Figs. 1 and 2, the bag is entirely closed

and the frames 1 are secured against the two sides or faces of the intermediate frame 4. At this time the catch 14 is abutting the stops 13 and 19, being in engagement with the frame member 4 and rail 11 of the member 1 which is presented to the observer. On the side of the bag which is turned away from the observer the catch 14 projects into the space 12, so that this catch is now effective to hold one frame member 1 against the intermediate member 4. The other catch 18 also abuts the stop 19, and on the side presented to the observer it fills the space 12 between the ribs 11 and 11—a; but on the opposite side it engages the rib 11 of the other plate 10 on the other frame member 1 and closes the compartment or pocket 9 which opens between that frame member and the member 4.

To open one compartment of the bag one now slides the catch 14 to the right until it slips off the rib or flange 11 and upon the adjacent rib 17. This catch has in the course of its travel moved along the rib 11—a of the plate 10 attached to the other frame member on the opposite side of the bag; and it runs upon the matching rib 17 of the intermediate frame member 4 at that side also, so that when this catch finally reaches the loop 5 it no longer is effective to hold either frame member 1 against the intermediate frame member 4. The frame member 1 which is presented to the observer in Fig. 4, however, can now be pulled open to give access to the adjacent compartment 9; and the other frame member is now held by the catch 18 and the other compartment 9 remains closed. To open the other compartment the catch 18 is moved to the left; and in so doing it travels along the rib 11 of the strip 10 secured to the other frame member 1 until it runs off this rib and upon the two short ribs or rails 17 at the adjacent end of the intermediate member 4 on both faces of the latter. Then the other frame 1 can be swung upon its hinges to open the remaining compartment 9. If the catch 18 were moved alone, the catch 14 remaining in mid position, the first pocket would remain shut and the catch 18 would run on the rib 11—a presented in Fig. 2 and along the rib 11 on the opposite side of the bag until it slides off the both of these ribs upon the adjacent ribs 17. Then the compartment on the side of the bag turned away from the observer could be opened, while the one on the side shown in Figs. 4 and 6, will stay closed. With this construction the receptacle has two pockets therein with very simple means for keeping both pockets shut or enabling both or one to be opened. Although the two sliding catches mounted to travel upon the rail shaped top of the intermediate frame 4 engage the ribs 11 and 11—a along the projecting upper edges of the two strips 10, neither interferes

with the other; because when one catch is moved to release position the space 12 between the ribs 11 and 11-a of the strip 10 of the frame member 1 of the pocket which this catch controls affords clearance to the other catch, so that the other catch will not prevent the desired pocket from being opened. At the same time a symmetrical construction and disposition of parts comprising 10 ribs 11, 11-a and 17 together with the two elements 14 and 18 on both sides of a line running vertically through the middle of the bag is afforded.

The principle of this invention can be utilized of course, upon valises, suit cases, vanity cases, watch cases and other containers as well as folding hand bags as shown.

I claim:—

1. Securing means for a receptacle comprising a body containing a plurality of pockets, said means including frame members hinged together to which the mouths of said pockets are to be secured, and sliding means engaging the frame members to secure and release same and permit access to said pockets.

2. Securing means for a receptacle comprising a body containing compartments, said means including, a pair of frame members to be secured to the edges of the mouth of the body, an intermediate frame member, to which one side of all the compartments is to be secured, and sliding catches mounted on the intermediate frame member to engage the first named frame members to keep the compartments closed or enable them separately to be opened.

3. In securing means for a receptacle of the class described, a pair of main frame members pivoted together, a supplemental frame member pivotally connected with said main frame members intermediate the same, and sliding means mounted on said supplemental frame member, said sliding means being adapted to engage the main frame members to hold them in closed position during the sliding movement, and said main frame members having portions adapted for disengagement of the sliding means to permit opening 50 of the receptacle.

4. Securing means for a receptacle comprising a body with compartments in said body, said means including frame members to be secured to the edges of the mouth of the body, a supplemental frame member between the first frame members, a partition attached to the supplemental member, said supplemental member being rail-shaped and having relatively short ribs at its ends at both sides 60 thereof, a pair of ribs rigid with each of said first-named frame members carried above the tops thereof in line with the ribs on the supplemental member, the ribs rigid with the first-named frame members being spaced 65 apart and one of said ribs being associated

with a stop, and a pair of catches mounted on the top of the supplemental member to slide along same and hold the first-named frame members against the supplemental member, said catches being separately movable along 70 the ribs rigid with the first-named frame members into engagement with the ribs at the ends of the supplemental member to release the first-named frame members separately to give access to said compartments. 75

5. Securing means for a receptacle having a mouth and a pair of pockets inside said means comprising a pair of inverted U-shaped frame members hinged together at their ends, the edges of said mouth to be secured to said 80 frame members; an intermediate frame member of similar shape hinged to the first-named members at the points of connection of the latter, plates along the inner edges of the first-named frame members, said plates having one 85 edge projecting above the tops of the first named frame members for a portion of the length of the tops, each of said plates having ribs extending along said edge, said ribs being separated by a space, a stop carried by each of said plates adjacent the middle thereof at the end of one of the ribs thereon, ribs on 90 both sides of the intermediate member at each end of said member in line with the ribs on said plates, a centrally located stop projecting above the top of the intermediate frame member, and sliding catches mounted on the intermediate frame member and shaped to engage the ribs of both of said plates, said catches being movable to release the first-named 95 frames separately to give access to either of said pockets.

6. Securing means for a receptacle comprising a plurality of compartments consisting of walls with mouth openings between the walls, said means including a pair of outer frame members and an inner intermediate frame member hinged together, the outer frame members carrying the outer walls of the compartments and an upwardly extending strip on the inner walls thereof with a laterally extending rib portion thereon and the inner frame member carrying the inner walls thereof, and a pair of sliding catches 105 engaging the ribs of the outer frame members to secure and release the intermediate and outer frame members with the mouth openings between the walls in closed and open condition, respectively, said sliding catches being operable independently of each other to allow the release of one outer frame member while the other outer frame member is secured. 110

7. In a folding receptacle securing means comprising a pair of outer frames and an intermediate frame member with their ends hinged together, said frames having upwardly extending strips on the inner wall thereof and provided with lateral edge ribs thereon, and the intermediate member being provided 125 130

with an extending edge portion having a groove therein, and a pair of sliding catches engaging the outer and intermediate frames to secure and release the same in closed and open position respectively, said sliding catches being operable independently one of the other to allow the release of one outer frame while the other is secured to the intermediate frame member.

10 In testimony that I claim the foregoing as my invention, and have signed my name here-to.

ANTON ZEINDLHOFER.
